UNITED STATES PATENT OFFICE.

MIRABEAU SIMS, OF PHILADELPHIA, PENNSYLVANIA, ASSIGNOR TO J. A. HORNER, OF BATH, PENNSYLVANIA.

MEANS FOR STREET CLEANING.

Application filed January 6, 1920. Serial No. 349,790.

To all whom it may concern:

Be it known that I, MIRABEAU SIMS, a citizen of the United States, residing at Philadelphia, county of Philadelphia, State 5 of Pennsylvania, have invented a new and useful Means for Street Cleaning, of which the following is a specification.

The invention relates to improvements in means for street cleaning, and it has for its 10 object generally to provide an apparatus which is efficient for street cleaning purposes and which is relatively simple as to construction and operation.

A further object of the invention is to 15 provide a street cleaning apparatus comprising means attached to a vehicle for sweeping and gathering the dirt and dust upon a street or other place into ridges or windrows and positively collecting the same by pneumatic means and depositing it in a tank or receptacle by such means.

A further object of the invention is to 20 provide novel means whereby the brushes or sweepers upon the vehicle may be manipulated readily and controlled.

A still further object of the invention is to 25 provide novel means whereby the tank or receptacle may be tilted to discharge therefrom dirt or refuse which may have been deposited therein without disturbing other parts of the structure.

Other objects and advantages of the invention will be pointed out in the detailed description thereof which follows or will 30 be apparent from such description.

Referring to the drawings which illustrate merely by way of example suitable means for the embodiment of my invention:—

Fig. 1 is a side elevation of a device embodying my invention.

Fig. 2 is a plan view of same.

Fig. 3 is a sectional end elevation on line 3-3 of Fig. 2.

Fig. 4 is a horizontal plan of the brushes 45 and adjacent parts on an enlarged scale, on line 4-4 of Fig. 3.

Fig. 5 is a detail elevation of the brush operating and supporting means.

Fig. 6 is a detail of the tank tilting mech- 50 anism.

Fig. 7 is a vertical cross-section of the rotor or exhauster on an enlarged scale.

Fig. 8 is a horizontal section on line 8-8 of Fig. 7.

Fig. 9 is a detail of the pneumatic pipe 55 joint.

Fig. 10 is a detail showing means for heating the material passing through pipe 26.

Similar numerals refer to similar parts throughout the several views.

To the frame portion 11, of a standard motor truck, is secured the receptacle or tank 12, by means of the pivotal connections 13 at the rear end of said frame 11. The front end of the tank 12 rests upon a support or cradle 14. The tank is held in the normal or horizontal position as shown in Fig. 1, primarily by its weight to the left of the pivot support 13, but any jolting or accidental movement of the tank is prevented by means of the link member 15, pivotally connected at one end, as at 16, to the tank, and at the other end, as at 17, to a threaded nut 18 mounted on the screw 19. The screw 19 is journaled in bearings 20 secured to the frame 11. This screw is connected by the worm gear 21 with a hand crank 22 for manual operation. So that by turning the hand crank 22 the nut 18 is moved along the screw 19, thereby causing the tank 12 to 70 assume the tilted position, as shown in dotted lines in Fig. 1.

At the lower rear end of tank 12 is provided the port having an airtight closure 23, hinged at 24 and provided with a suitable 85 catch 25, for normally maintaining the same in airtight closed position.

Connected to the front end of this tank is the material conveying pipe 26, which extends vertically to the upper part of the tank to a wide radius curve 27, discharging to the upper forward end of said tank. This pipe 26 has a disengageable connection with a stationary pipe section 28, which is secured to the frame 11. To the lower end of pipe 90 section 28 is secured a flexible pipe section 29; the lower end of section 29 is connected to and supports a nozzle section 30 which is preferably made of bronze or similar metal and constitutes the intake end or nozzle for material to be conveyed and delivered by 95 26 to tank 12. This nozzle projects to within a few inches of the ground and is preferably provided at its lower intake end with a rubber buffer section 31 for the purpose of preventing shock to the metal in case an obstruction is encountered. Mounted on the 100 body portion 11 of the truck just in front 105

of the tank 12 is the rotary blower or exhauster 32 which will be referred to herein-after as the rotor. This rotor or exhauster is of the cycloidal or positive type and a comparatively low speed machine. This device is shown more in detail in Figs. 7 and 8. The impellers 33 having a very slight clearance with the interior walls of the casing and also between each other, namely about 10/1000 of an inch, so that each revolution of the impeller draws in and discharges a known and fixed quantity of air so that the quantity of air discharged on each revolution multiplied by the number of revolutions per minute gives the volume in cubic feet per minute. The rotor is connected with the tank 12 by the pipes 34 and 35. These pipes have a disengageable airtight connection at 36 which consist of cone and funnel shaped rubber gaskets, one tending to fit within the other so that upon suction through the pipe, the below atmospheric pressure will tend to make said connecting elements effective in securing an airtight joint. A similar disengageable airtight connection is provided at 37 between pipe sections 26 and 28. This arrangement permits the tilting of the tank as above described and the automatic airtight connections between the pipings when the tank is brought back into normal position as shown in Fig. 1. The pipe 35 extends horizontally within tank 12 to near the rear end of the tank so that air is drawn from the tank at a point as remote as practicable from the point of discharge of pipe 26 and discharge end 27. The screen 38 is provided in the top of tank 12 interposed between the discharge end 27 of pipe 26 and the intake end of pipe 35. This screen is preferably made in undulating formation to present a greater area of effective surface.

A relief valve is connected with the rotor preferably in pipe 34 near its connection with the rotor 32. This comprises a chambered body or casing 40 having the port 41 with a seat 42 consisting of an annular knife-edge formation with which cooperates the valve member 43 having the ring 44 of Babbitt metal for engaging the knife-edge formation 42. To valve 43 is secured the spindle 45 which projects upwardly through the casing and is provided above the casing with a number of removable weights. The purpose of this relief valve is to prevent an overload on the system in the following manner. If the system is set to operate on a partial vacuum of say two inches of mercury or one pound minus pressure, then the weights 46 on the top of the relief valve are placed accordingly so that when the system is loaded beyond its predetermined pressure capacity, the valve will automatically break the vacuum, by-pass the column of air and temporarily relieve the

pressure on the pipe lines, thus automatically adjusting itself to the fluctuations of varying loads. The impellers 33 are rotated by the motor or engine 47 through belt 48 and gears 49 and 50. The air discharging from the rotor is delivered into the pan 39 beneath the level of water contained therein for the purpose of collecting and washing out any dust or gases that may be drawn from the tank 12.

Suitably mounted beneath the truck are the cylindrical brushes 51 and 52. These brushes are journaled in bearings such as 53, mounted on brackets 54 pivoted at 56 to a part 57 rigidly connected with truck body 11. The upper end 58 of bracket member 54 is connected to a chain 59 or other suitable flexible connection running over pulley 60 to a suitable actuating device such as lever 61 so that such bearing 53 may be raised and lowered as required. Each bearing of the two brushes being similarly supported; it follows that the brushes may be lifted either at one end or both ends as desired. Upon the axis 62 of the brush is secured the sprocket wheel 63 which is connected by a sprocket chain 64 with the sprocket 65. Sprocket 65 is connected by suitable gearing 66 with the axle or wheel of the truck so that, with proper reductions, the brushes 51 and 52 may be made to revolve at any desired ratio with respect to the wheels of the truck. The sprocket wheel 65 is mounted on a countershaft extending the length of the brush and provided with corresponding sprocket wheel 65' and chain 64' so that each brush is driven from both ends thereof. Above the brushes 51 and 52 is provided the sheet metal cover 67. To this sheet metal cover is connected a suitable canvas curtain 69 which extends down and around the sides and ends of the brushes to within an inch or two of the surface to be operated upon. The purpose of these curtains is to prevent a scattering of the dust and dirt being operated upon by the brushes.

A conduit or passageway 71 is provided through which heated gases from the exhaust of the engine employed for driving the blower 32 are conducted to the material pipe 26 where it operates for heating and melting any snow which may be conveyed through the said pipe to the receptacle or tank 12.

A port 72 is provided in connection with the tank or receptacle 12 for connection with a special pipe or conveyor leading to an ash bin in cellars or similar storage of material to be removed.

What I claim is:—

1. In street cleaning apparatus, the combination of a vehicle, a tank supported thereon, a suction nozzle and means connecting the same with the tank, an exhauster connected with the tank having rotating impellers adapted to and capable of drawing

in and discharging a definite quantity of air with each revolution, and an adjustable pressure relief valve comprising a gravity actuated valve member engaging a knife edge annular seat, adapted to yield to the pull of the exhauster and automatically operating to maintain a substantially predetermined and constant pressure in the tank.

- 10 2. In street cleaning apparatus, the combination of a vehicle, a tank supported thereon, a suction nozzle and means connecting the same with the tank, an exhauster connected with the tank, and means permitting a separation of elements in the connecting means between nozzle and tank, when the tank is tilted, and for automatically making said pneumatic connection again, when the tank is restored to normal, comprising cone and funnel shaped members with a cooperating gasket, arranged to increase the efficiency of the joint with suction pressure in the pipe.
- 15 3. In street cleaning apparatus, the combination of a vehicle, a tank supported thereon, a suction nozzle and means connecting
- 20 the same with the tank, an exhauster connected with the tank, said exhauster comprising a rotor, an internal combustion engine for driving said rotor, and means for communicating the heat from the engine exhaust to the path of travel from nozzle to tank, as and for the purpose described.

the same with the tank, an exhauster connected with the tank, said exhauster comprising a rotor, an internal combustion engine for driving said rotor, and means for communicating the heat from the engine exhaust to the path of travel from nozzle to tank, as and for the purpose described.

4. In a street cleaning apparatus, the combination of a vehicle frame, a tank pivotally connected to said frame, means for effecting pivotal movement of said tank, an exhaust pipe carried by said tank the outer end of which extends downwardly and is provided with a hood, an exhauster having a pipe which projects into the said hood and contacts with the outer end of said first mentioned pipe, a second pipe carried by said tank and projecting thereinto, the outer depending end of which is provided with a hood, a nozzle supported upon the said frame and the upper end of which projects into said hood and contacts therewith and with the lower end of the said third mentioned pipe, substantially as described.

MIRABEAU SIMS.
